UNITED STATES PATENT OFFICE.

CHARLES L. DE MARTIN AND WILLIAM M. MATTEOLI, OF CONNERSVILLE, AND SAMUEL F. ARBUCKLE, OF INDIANAPOLIS, INDIANA, ASSIGNEES, BY MESNE ASSIGNMENTS, TO UNITED STATES AUTOMOTIVE CORPORATION, OF CONNERSVILLE, INDIANA, A CORPORATION OF DELAWARE.

LAMP CONSTRUCTION.

1,376,191.

Specification of Letters Patent. Patented Apr. 26, 1921.

Application filed June 2, 1919. Serial No. 301,360.

To all whom it may concern:

Be it known that we, CHARLES L. DE MARTIN, WILLIAM M. MATTEOLI, and SAMUEL F. ARBUCKLE, citizens of the United States, and residents of Connersville and Indianapolis, counties of Fayette and Marion, and State of Indiana, have invented a certain new and useful Lamp Construction; and we do hereby declare that the following is a full, clear, and exact description thereof, reference being had to the accompanying drawings, in which like numerals refer to like parts.

This invention relates to the construction of a lamp or headlight for automobiles, motor boats and the like, and more particularly to that type of headlight in which a tilting reflector is used.

The main object of this invention is to construct a tilting reflector headlight in the most convenient and practical manner for assembly and operation, whereby the various working parts are formed and held together so as to be readily demountable from the headlight casing. This is accomplished by means of a metal bow to which is secured the reflector, lamp and controlling means, whereby all operable parts are contained within and supported by said bow, which may be readily mounted in or removed from the casing without disturbing said operable parts.

In the drawings, which are made a part of this application, Figure 1 is a central vertical cross section through the lamp showing the reflector in tilted position. Fig. 2 is the same as Fig. 1 showing the reflector in normal position. Fig. 3 is a front elevation of the lower portion of the reflector showing the method of hinging it to the casing. Fig. 4 is an enlarged section taken on the line 4-4 of Fig. 3 showing the hinge construction. Fig. 5 is a front elevation of the upper portion of the lamp with the reflector removed therefrom.

In the drawings there is shown a lamp casing 10, parabolic in form, having a door rim 11 mounted thereon, in which is secured a lens 12 by means of a plurality of spring clips 13 mounted on corresponding lens spacing members 14, there being approximately three lens retaining clips and spacing members spaced around the periphery

of the door rim. The casing 10 is provided with an inwardly extending flange 15 about its periphery, against which a retaining rim 16 is adapted to abut, being held in position by the lens 12 pressing against the packing ring 17 so as to force the rim 16 against said flange. Mounted and supported by said retaining rim there is a metallic strip 18, formed bow-shape so as to extend around and lie adjacent the inner wall of the casing and to embrace the reflector 19. The reflector 19 is hinged to the retaining rim 16 at two points 20, on either side of the bottom thereof, as shown in Fig. 3, by means of a hinge member 21, which consists of a spring member looped so as to engage the inwardly turned open bead of the reflector 19 by means of a downwardly curved projection, and clamp itself on to the retaining rim, as shown in the enlarged section of Fig. 4, whereby said reflector may be tilted within the stationary retaining rim 16. The reflector may also be hinged at any other points on its periphery, such as the sides thereof, without departing from this invention.

Mounted on the inner side of the supporting bow 18 there is a fluid actuating means 22, shown herein as a bellows, however a piston or any other suitable means may be used in this construction. Said fluid actuating means is secured at one end to said bow and at the other end to the lower portion of the reflector so that it will draw said reflector rearwardly to its normal position, as shown in Fig. 2, when compressed, and force it forwardly to the tilted position, as shown in Fig. 1 when expanded.

Mounted in the reflector there is a lamp 23 secured in the socket 24 extending rearwardly from said reflector, and having an upwardly extending arm 25 which is adapted to straddle an adjusting bolt 26 which extends through the supporting bow horizontally and is provided with adjustable nuts 27, which further act as a stop whereby the limiting of the forward and rearward movement of the reflector may be further adjusted. Secured to the upper portion of the bow there is a leaf spring 28, in position to yieldingly engage the projection 29 secured to the reflector, for exerting a slight forward and downward pressure on said re-

flector to aid the fluid actuating means in its tilting movement, and maintaining the reflector in its upper position relative to the hinges and retaining rim and also prevent 5 any play or rattle of the reflector therein.

The tube 30 leading to the fluid actuating means, and the conduit 31 leading to the lamp socket extend into the contact plug 32, whereby removable contact may be made 10 with the fluid and electric conduits.

The construction is therefore such that the lamp is formed in three adjustable parts, namely the door, operating parts and the casing, and is therefore simple in its adjustment and repair, inasmuch as all of 15 the working parts can be removed at one time from the casing and retain their respective working positions relative to each other.

20 The invention claimed is:

1. A lamp construction including a casing, a door mounted on said casing, an annular rim removably secured on said casing, a tilting reflector pivotally mounted on said 25 rim, a frame member spaced from said reflector and secured to said rim, said frame member extending between said reflector and casing, and means supported between said frame member and reflector for actuating said reflector, whereby said reflector, 30 actuating means and supporting rim and

frame may be removable from said casing as a unit.

2. A lamp construction including a casing, a door mounted on said casing, a retaining rim mounted in said casing, a tiltable reflector mounted on said rim, means for tilting said reflector, a single means mounted on said retaining rim for supporting and retaining said tilting means in constant relation with said reflector, means mounted in 35 said supporting means for adjusting and limiting the tilting position of said reflector, and resilient means for yieldingly retaining said reflector in its tilted position. 40

3. A lamp construction including a lamp casing, a door removably mounted on said casing, a retaining rim supported between said door and casing, a reflector mounted in said rim and having a rearwardly turned 50 bead, means for tilting said reflector, and a spring clip having a forward and downward projection adapted to engage in the rearward turned bead of said reflector and frictionally secure it on said rim for hinging 55 said reflector thereon, whereby it will be tiltable in said casing.

In witness whereof, we have hereunto affixed our signatures.

CHARLES L. DE MARTIN.
WILLIAM M. MATTEOLI.
SAMUEL F. ARBUCKLE.
